GARMENT RACK OR THE LIKE

William H. Brown, Jr., 724 Poplar Ave.,
Carrboro, N.C. 27510

Filed July 19, 1971, Ser. No. 164,181

Term of patent 14 years

Int. Cl. D6—06

U.S. Cl. D6—85

FIG. 1 is a front elevational view of a garment rack or the like showing my new design;

FIG. 2 is a side elevational view thereof;

FIG. 3 is a top plan view thereof;

FIG. 4 is a perspective view thereof; and

FIG. 5 is a perspective view of a modified form of the garment rack or the like shown in FIG. 1.

I claim:

The ornamental design for a garment rack or the like, as shown and described.
